UNITED STATES PATENT OFFICE.

FRANK FAHSBENDER, OF PATERSON, NEW JERSEY.

LIFTING DEVICE.

Application filed November 14, 1921. Serial No. 514,984.

To all whom it may concern:

Be it known that I, FRANK FAHSBENDER, a citizen of the United States, and resident of Paterson, in the county of Passaic and 5 State of New Jersey, have invented a new and Improved Lifting Device, of which the following is a full, clear, and exact description.

In connection with receptacles, it is a well 10 appreciated fact that considerable difficulty has been experienced in lifting the same, when they are highly heated, and are not provided with properly insulated handles.

A further difficulty has been experienced 15 in that receptacles containing acids, or a similar substance, have presented difficulty in being moved, due to liability of the contents to splash the hands of the person moving the same.

20 Thus my present invention aims to provide a receptacle lifter by means of which a receptacle may readily be gripped, and subsequently lifted and carried without an operator endangering his hands either by 25 heat, or due to the contents of the receptacle.

Still a further object of this invention is 30 the provision of a device of the character stated which is extremely simple in construction, and capable of being manufactured at a nominal cost, aside from the fact that the simplicity of construction will at 35 all times insure a positive operation, and reduce the danger of breakage occurring to a minimum point.

Still further objects of this invention will 40 become apparent in the annexed specification taken in connection with the drawings, which latter illustrate one practical embodiment of the same, and in which:

Figure 1 is a side view of a lifting device embodying my improved construction, and showing the same in use, and

Figure 2 is a plan view thereof.

45 Referring now more particularly to Figure 1 it will be seen that the reference numeral 5 indicates a central main structure preferably formed with a transverse vertical elongated opening 6, which latter permits of the passage of the operator's fingers. A trigger 7 is rockingly secured as at 8 to the grip 5 and it will be obvious that upon the operator grasping the structure 5 in the manner indicated in Figure 1 that the trigger or handle 7 will have its lower end

swung inwardly, i. e. towards the structure 5.

It will also be noted, as in Figures 1 and 2, that a rod 9 has one of its ends rockingly attached to the upper end of the handle 7, 60 and its body extends through a bore in the structure 5, it being noted that its opposite end projects beyond this member, and is readily connected to a jaw 10. Thus upon the parts being actuated in the manner 65 aforescribed, it will be obvious that the jaw will be drawn towards the vertical elongated part of the structure 5 which lies between the jaw 10 and opening 6; it thus being seen that the two parts last mentioned 70 comprise a pair of gripping members for the article to be lifted. It will also be seen that the part of structure 5 which lies between the handle or trigger 7 and the opening 6 constitutes, with the trigger 7, what 75 may be termed a pair of handle members. It will be noted that all four gripping and handle members extend substantially parallel, thus making the new lifting device exceedingly sturdy and compact. 80

A main structure 6 may be provided with a groove as shown to accommodate the bead of a receptacle to be lifted.

Thus all of the objects of this invention have been accomplished and it will further 85 be understood that numerous modifications of structure might readily be resorted to without in the least departing from the scope of my claims, which are:

1. A lifting device comprising the combination of a pair of relatively movable gripping members and a pair of relatively movable handle members, all four such members being substantially parallel, and an operative connection between one member of one pair and one member of the other pair whereby a movement of one handle member relative to the other effects a movement of one gripping member relative to the other. 90

2. A lifting device comprising the combination of a pair of relatively movable gripping members and a pair of relatively movable handle members, all four such members being substantially parallel, and an operative connection between one member of one pair and one member of the other pair whereby a movement of one handle member relative to the other effects a movement of one gripping member relative to the other, said connection including a sliding member 100

fixedly carrying one gripping member and pivotally connected to one handle member, the two other members being bored laterally to slidingly receive said sliding member.

5 3. The lifting device defined in claim 2, wherein the two bored members are parts of an O-shaped main structure.

4. A lifting device including a central main structure comprising a block having a 10 transverse vertical elongated opening, a rod slidably mounted on the upper portion

of said block, a jaw rigidly attached to one end of the rod on one side of the block, and a member pivotally mounted intermediate its ends on the other side of the block, said member being adapted to be gripped by the palm of a hand the fingers of which grasp said block by way of its opening, said member at its upper end being pivoted to the other end of said rod. 15

FRANK FAHSBENDER.
